TAPE HANDLING MECHANISM

William H. Uhl, Penfield, and Edward G. Ziegelhoefer, Rochester, N. Y., assignors to Commercial Controls Corporation, Rochester, N. Y.

Application December 2, 1949, Serial No. 130,702

15 Claims. (Cl. 101—227)

1

This invention relates to an improved tape handling mechanism for a postage printing machine.

Most modern postage printing machines are capable of printing postage on gummed tape, as well as on cards or envelopes. Thus these machines include mechanism adapted to automatically feed the gummed tape into printing position relative to the printing head of the machine, sever the tape at the proper time, and moisten it or not, as desired. Certain well-known devices of this nature have met with a degree of commercial dissatisfaction by reason of structural complexity, rendering repair difficult, uncertain operation under conditions of unusually high humidity, and recurrent tape jams causing loss of postage value, as well as the loss of time necessary to clear the machine. Still others, because of the location of the tape severing mechanism in relation to the nip between the printing head and platen, require operating mechanism capable of retracting tape after it has been cut off at the finish of the operating cycle and of advancing the tape to proper printing position, but prior to the printing operation at the beginning of the operative cycle. If such retracting and advancing operations are not properly and precisely effected, there is always a chance that the postage value will be improperly imprinted on the tape. Indeed, sometimes postage is lost through improper advancing of the free end of the tape.

It is accordingly among the objects of this invention to provide a tape feeding mechanism for a postage printing machine which obviates the foregoing difficulties, as well as others, in a thoroughly practical and efficient manner.

The invention accordingly consists in the features of construction, combination of elements, and arrangement of parts, all as will be exemplified in the structure hereinafter described, and the scope of the application of which will be indicated in the following claims.

In the drawing, wherein there is shown an illustrative embodiment of my invention.

Figure 1 is a sectional elevation of the tape feeding mechanism set in operative position,

Figure 2 is a fragmentary view similar to Figure 1, but showing the mechanism set in inoperative position; and

Figure 3 is a section taken along the line 3—3 of Figure 2.

Similar reference characters refer to similar parts throughout the views of the drawing.

In accordance with one form of our invention, 55 15, secured to the base plate 16 of the machine.

2

the printing head and platen are rotatably juxtaposed, the platen being carried by pivoted supporting plates spring-biased toward the printing head. A pair of tape feed rollers are rotatably carried by these plates adjacent the platen, and when driven feed the tape through a cut-off device to the nip between the printing head and platen. The platen axle rockably supports a yoke which carries an idler, which is engageable with so as to be driven by the platen. When this yoke is swung toward one of the tape feed rollers, the idler first engages the platen then the roller, and being driven by the platen, drives the roller causing it to feed tape. Movement of the idler into engagement with the platen and the tape feed roller is effected by way of a system of levers operated by a cam carried by the printing head, and this lever system can be swung between operative and inoperative positions, as it is desired to set the machine. The printing head also carries a settable arm which can be set to trip a trip lever which effects actuation of the cut-off device whereby long or short strips of tape may be cut off between successive printing operations. This arm is so mounted on the printing head as to actuate the cut-off device at the proper time, the cut-off strip of tape being fed by reason of the engagement thereof by the type on the printing head. Thus the mechanism acts in a simple and efficient manner to feed the free end of the tape to proper printing relation in relation to the nip between the printing head and platen, with the proper length of tape being automatically cut off at the proper time, there being, accordingly, no necessity to retract the tape subsequent to either the printing operation or the cut-off operation. At the exit end of the nip between the printing head and platen is a deflector or guide which, when the machine is set for tape printing, is moved into proper position to guide the tape to a moistening device (not shown), but which is removed from the path of envelope travel when the machine is set to print on envelopes.

Referring now to Figure 1, most of the structural elements constituting the tape feed mechanism are supported by a pair of parallel plates, one of which is shown at 10 in Figure 1, and the other of which is shown at 11 in Figure 3. As shown in Figure 1, these plates constitute a carriage, generally indicated at C, which is pivotally supported on a shaft 12 supported by suitable framework (not shown). This carriage also carries another shaft or stud 13 to which is fastened a bracket 14, mounted on the upper end of a rod 15, secured to the base plate 16 of the machine.

A spring 17 interposed between base plate 18 and the bottom of bracket 14 constantly biases the carriage upwardly toward a printing head 18. This printing head is carried by a shaft 19, which is rotatably mounted in conventional manner in the machine frame (not shown). Carriage C rotatably supports a platen 20 which is mounted on a shaft 21, journaled in the carriage side plates. This shaft is adapted to be constantly rotated when the machine is in operation, by any suitable driving mechanism (not shown). As the platen is carried by the carriage C, it is accordingly movable therewith toward and away from printing head 18 in order to accommodate pieces of mail matter of various thickness passing through the nip and between the printing head and platen. In the upper left-hand portion of carriage C is rotatably mounted a guide roller 22 which coacts with a pressure roller 23 to feed envelopes or cards toward the printing head and platen over a trip arm 24. As these devices are of conventional nature, it will suffice to point out that when a card or envelope is thus fed through these rollers 22 and 23, trip arm 24 is depressed to actuate the driving mechanism (not shown) which actuates printing head 18. Thus actuated, the printing head rotates through one revolution and prints postage value on the envelope.

The invention herein is concerned with the tape handling mechanism which will now be described. A stub 25 is supported on the machine frame, and this stub rockably mounts a tape feed mechanism positioning arm 26. The lower end of this arm is slotted as at 27 to receive a pin 28 carried by a manually operable lever 29 fastened to a shaft 30 rotatably mounted in any suitable manner in the machine frame. The upper end of a spring 31 is fastened to the pin 28, the lower end of this spring being anchored by a pin 32. When it is desired to print postage value on tape, lever 26 is in its Figure 1 position. When the machine is set for printing on envelopes or cards, this lever is rocked to its Figure 2 position, spring 31 being so arranged in relation to the lever that the lever is releasably held in either of its set positions. With lever 29 in its Figure 1 position, arm 26 is in a substantially vertical attitude. On the upper end of arm 26 is pivotally mounted a bell crank lever, generally indicated at 33, one arm 34 of which carries a roller 35, the other arm 36 of which is pivotally connected to the upper end of a link 37. Roller 35 is adapted to coact with a cam 38 secured to and accordingly rotatable with printing head 18.

The lower end of link 37 is pivotally connected to a lever 39, fastened to a shaft 40 rotatably mounted in any suitable manner in the machine frame. This shaft 40 also has secured thereto an arm 41 provided with a cam surface 42. It may now be seen that when printing head 18 rotates counterclockwise, the cam 38 carried thereby moves from its initial or broken line position to and through the position shown by the dot-dash line. In so doing, surface 38a of the cam contacts roller 35 on bell crank 33, thus to rock the bell crank counterclockwise. This movement of the bell crank forces link 37 downwardly and accordingly through the lever 39 and shaft 40 rocks arm 41 and its cam 42 counterclockwise. After the printing head 18 has rotated sufficiently, its cam 38 rides past roller 35, permitting a spring 43 to rock bell crank 33 clockwise to its solid line or rest position, which movement, of course, restores arm 41 and its cam 42 to the position shown in Figure 1. This clockwise re-

turn movement of bell crank 33 is limited by a stop 44.

It is the cam 42 on arm 41 that effects the operation of a pair of tape feed rollers 45 and 46. These rollers are respectively mounted on shafts 47 and 48, journaled in the side plates of carriage C, the shafts carrying respectively gears 49 and 50, which are in constant mesh. Thus, as roller 48 is driven in a manner to be described, roller 45 is also driven by way of the gears 49 and 50. These tape feed rollers 45 and 46 are located at opposite sides and near the upper end of a tape chute generally indicated at 51, this chute being formed by an upper plate 52 and a lower plate 53. The lower end of chute 51 lies adjacent a tape supply housing 54, within which is adapted to be disposed a roll of tape 55.

On platen shaft 21 is rockably mounted a cradle, generally indicated at 56 (see Figure 3). This cradle comprises a pair of arms 57 and 58, which are loosely mounted at one end on platen shaft 21; thus the cradle arms straddle platen 20. Near the free end of each of these arms is a slot, such as slot 59 in arm 58 (see Figure 2). As shown in Figure 3, these slots receive the ends of a shaft 60, this shaft carrying an idler roller 61. The ends of shaft 60 project respectively through vertical slots 10a formed in plates 10 and 11. Near each end of the shaft and adjacent arms 57 and 58 are a pair of plates 62 and 63, to which are respectively fastened one end of springs 64 and 65, the other ends of these springs being suitably anchored to arms 57 and 58, respectively. Thus, by virtue of the slotted mounting of the ends of shaft 60 and the tension of springs 64 and 65, idler roller 61 is cammed into engagement with platen 20 by slots 10a during initial upward movement of cradle 56. The platen is, of course, preferably rubber surfaced, and so is idler 61, so there is a good driving connection therebetween.

Still referring to Figure 3, it may be seen that the left-hand ends of arms 57 and 58 have secured thereto a follower 66 and a rod 67, the former of which is adapted to coact with arm cam 42 (Figure 1) and the latter of which is adapted to receive a shoe 68 formed on the lower end of rod 69, the upper end of which extends slidably through a stationary lug or the like 70. A spring 71 is interposed between strap 70 and cradle 56, and this spring constantly biases the cradle downwardly maintaining its follower 66 in engagement with arm cam 42.

It will now appear that when arm 41 and its cam 42 are rocked counterclockwise in the manner hereinbefore described, cam 42, bearing against follower 66, forces cradle 56 clockwise against the pressure of spring 71 and accordingly lifts idler roller 61 from its solid to its dotted line position shown in Figure 1, first into engagement with platen 20 and then with tape feed roller 46. The idler, being in contact and accordingly driven by platen 20, thus acts to rotate tape feed roller 46 and accordingly tape feed roller 45 through the gears 49 and 50. As these tape feed rollers rotate, they feed tape toward the nip N between the printing head 18 and platen 20.

The tape feed rollers continue to feed tape as long as they are driven by idler 61, and idler 61 remains in its driving position as long as bell crank roller 35 is engaged by printing head cam 38. When this cam rides off the roller, the bell crank 33 and parts connected thereto return to the solid line position (Figure 1, thus permitting cradle 56 to drop down to its solid line position, disengaging idler 61 from tape feed roller 46 and

platen 20, thus discontinuing the feeding action of rollers 45 and 46. By this time, however, the free or leading end of the tape has been advanced to the nip N between the printing head and platen so that when the type face on the printing head comes around, it will engage the tape, and during the printing operation continue the feeding of the tape between the printing head and platen.

It is, of course, desirable to sever the printed end of the tape at the end of each cycle of operation. We have accordingly provided a settable device whereby separate successive cut-off strips may be delivered. Thus, as shown in Figure 1, printing head 18 carries a trip arm 72 which is pivotally fastened to one side of the printing head, as by a pin 73. This trip arm 72 is pivotable between its Figure 1 and Figure 2 positions. When in the Figure 1 position it is operative to actuate the tape cut-off mechanism so that the machine will deliver relatively short individual strips of tape; when this arm is in its Figure 2 position, wherein its leading end 72a is flush with, and its trailing end 72b projects from the periphery of the printing head, the tape cut-off device will operate later, and the machine will accordingly deliver a longer strip on which an advertising slogan or the like may be printed.

This trip arm 72 effects the operation of a tape severing device, generally indicated at 74 (Figure 1), in a manner that will now be described. The tape severing device includes a knife 75 fastened to an arm 76 pivotally attached to carriage side plates 10 and 11. The left end of arm 76 is pivotally connected to carriage side plates 10 and 11. The left end of arm 76 is pivotally connected to the upper end of a link 77, the lower end of which is slotted as at 78 to receive a pin 79 carried by the free end of a lever 80 fastened to shaft 46. When the severing device 74 is in operative position, i. e., the Figure 1 position, its right-hand end is supported by the tip 81 of a trigger lever 82. This lever is pivotally fastened to side plate 10 as by a pin 83, and is under a constant counterclockwise bias by reason of a spring 84, one end of which is fastened to side plate 10, and the other end of which is fastened to an upstanding arm 85 of the trigger lever. The lower end of the trigger lever terminates in an arm 86. It should be noted that arm 76 of the severing device is under a constant clockwise bias by reason of a spring 87, one end of which is fastened to arm 76, and the other end of which is anchored in any convenient manner.

In operation, and with the parts set as shown in Figure 1, the tape feed rollers 45 and 46 go out of operation before end 72a of trip arm 72 engages trigger arm 85, as printing head cam 38 has ridden past roller 35. Subsequently, trigger arm 85 is engaged by trip arm 72, forcing trigger lever 82 clockwise and pulling its tip 81 from beneath the spring-biased arm 76. The arm accordingly is snapped clockwise so that knife 75 suddenly severs the tape at the upper end of tape chute 51, but while the tape is being fed through the nip N of the printing head and platen, by the pressure of the type face on the tape. As the tape continues to be fed, its leading edge enters a deflector 88 pivotally mounted between the carriage side plates, as by a pin 88a, so that this end of the tape is deflected downwardly to a guide roller 89 which presses the tape against the surface of platen 20, thus operating to eject the severed piece of tape either into a suitable receptacle (not shown), if unmoistened tape is desired, or into a moistening

device (not shown), if moistened tape is desired.

When the knife arm 76 snaps over as described, it moves to the position shown in Figure 2, so that at such time pin 79 of lever 80 is in the lower end of slot 78 of link 77. Thus it follows that when bell crank 33 is rocked by printing head cam 38 in the manner hereinbefore described, lever 80 rotates counterclockwise with shaft 46, and in so doing pulls link 77 downwardly thus rocking knife arm 76 counterclockwise. As the right-hand end of the arm, as shown in Figure 1, rises, it ultimately engages beneath trigger tip 81, continued movement of the arm forcing the trigger lever clockwise until the arm rides past and above the tip, permitting spring 84 to pull the trigger lever counterclockwise so that the tip rides under the right-hand end of arm 76, thus to hold the knife arm in operative position. This restoring movement of the knife arm 76 occurs before idler 61 engages tape feed roller 46, so that the upper end of the tape chute is opened to permit the feeding movement of the leading end of the tape when idler 61 ultimately engages feed roller 46. It will accordingly appear that through a simple mechanism controlled directly by cam 38 on printing head 18, the tape severing device is conditioned for operation, and thereafter the leading end of the tape is fed into proper printing position at the nip end between the printing head and platen. At the proper time during the printing operation, the tape severing device is actuated as hereinbefore described, so that the proper length of tape is cut off, this cut-off strip thence being fed to the deflector 88 and ultimately ejected. Thus, at the end of the operative cycle, there is no need to retract the tape preparatory to the next cycle of operation.

When trip arm 72 is set in its Figure 1 position, i. e. that position wherein its end 72a is effective to actuate trigger lever 82, the cut-off strip of tape is relatively short. Many users of machines of this type, however, like to print on the strip an advertising slogan or the like, thus necessitating a longer strip. Under such circumstances, the arm 72 is set in the position shown in Figure 2, wherein its end 72a is flush with the periphery of printing head 18, whereas its end 72b projects therefrom, thus enabling this end 72b to engage arm 85 of trigger lever 82. This engagement, however, occurs at a later time than the engagement between end 72a and arm 85 would occur, and accordingly the printing head and platen are enabled to continue to feed tape a longer period of time. This, of course, results in a longer strip.

As pointed out hereinbefore, the manually operable lever 29 is settable between its Figure 1 and Figure 2 positions, depending on whether it is desired to print postage value on tape or on envelopes. When envelopes are to be fed into the machine, this lever 29 is shifted to its Figure 2 position. In so doing, arm 26 is rocked counterclockwise, and this moves bell crank 33 and accordingly its cam follower roller 35 to the left so that the roller is shifted out of the path of movement of printing head cam 38. Accordingly, when the printing head rotates, the cam will not contact roller 35, and the tape handling mechanism will not be actuated. Also, when lever 29 is shifted to envelope printing position, a pin 90, carried by an arm 91, fastened to shaft 30, engages arm 86 of trigger lever 82, shifting the trigger lever clockwise, to remove its trigger arm 75 85 to the right of and somewhat below nip N,

thus removing the trigger arm from the path of travel of cards or envelopes passing through the machine.

This movement of lever 29 to envelope printing position also affects tape guide or deflector 88. As shown in Figure 1, deflector 88 carries a small pin 92 engageable by the upper end of a slidable bar 93, slidably mounted on pins 94 carried by side plate 11. The lower end of this bar is widened at 93a and rests on a pin 95 carried by an arm 96 fastened to shaft 38. Thus when lever 29 is in its tape printing position, pin 95 forces bar 93 upwardly and accordingly pivots deflector 88 clockwise into its tape deflecting position, as shown in Figure 1. When, however, lever 29 is swung to its letter printing position, as shown in Figure 2, pin 95 rides from beneath foot 93a of bar 93, permitting the bar to drop and the deflector 88 to rock counterclockwise, which lowers its upper end out of the path of travel of the envelopes as they pass through the nip N. Thus it follows that lever arm 29, when moved to its Figure 1 or tape printing position, conditions the tape feed roller actuating mechanism for operation, moves the trigger lever 82 into operative position where it can control knife arm 76, and elevates bar 93 to rock the tape deflector 88 into its operative position.

Thus it may be seen that we have provided a tape handling mechanism which attains the several objects set forth hereinabove in a thoroughly practical and efficient manner.

We claim:

1. In a tape feeding mechanism for a postage printing machine capable of printing postage on envelopes or tape, the combination of, a frame, a platen rotatably mounted on said frame and adapted to rotate constantly while the machine is in operation, a printing head adapted to rotate cyclically, means forming a tape feed device mounted on said frame adjacent said printing head and platen and adapted when actuated to feed tape toward the nip between said printing head and platen, a driving member movably supported on said frame for movement into engagement with said platen so as to be driven thereby, means operable to move said driving member into engagement with said platen, and actuating means operatively associated with said printing head and with said driving member and actuated by said printing head during its cycle of operation to move said driving member into driving relation with said tape feed device, whereby said tape feed device is actuated to feed tape.

2. In a tape feeding mechanism for a postage printing machine capable of printing postage on envelopes or tape, the combination of, a frame, a platen rotatably mounted on said frame and adapted to rotate constantly while the machine is in operation, a rotatable printing head operatively mounted in said machine in printing registry with said platen, means forming a tape feed device mounted on said frame adjacent said printing head and platen and adapted when actuated to feed tape toward the nip between said printing head and platen, a driving member movably supported on said frame for movement into engagement with said platen so as to be driven thereby, means operable to move said driving member into engagement with said platen, a driving element carried by said printing head and rotatable therewith, and a driven system operatively associated with said driving element and said driving member and actuatable by said driving element during a portion of each

revolution of said printing head to move said driving member into driving relation with said tape feed device, whereby said tape feed device is actuated to feed tape.

5 3. Apparatus according to claim 2, wherein said driving element comprises a cam and said driven system comprises a series of interconnected levers, one of said levers being periodically engageable by said cam, whereby all of the levers are driven, another of said levers being operatively associated with said driving member.

15 4. Apparatus according to claim 1, wherein said driving member comprises a roller, means including an arm for supporting said roller, and spring means operatively associated with said roller for biasing it toward said platen said tape feed device including a roller engageable by said driving roller to be driven thereby.

20 5. Apparatus according to claim 1, wherein means are provided to move said actuating means between operative and inoperative positions depending on whether the machine is set to print postage on tape or envelopes.

25 6. Apparatus according to claim 1, wherein said tape feed device comprises a pair of rollers positioned and adapted to engage opposite sides of the tape.

30 7. Apparatus according to claim 1, wherein said tape feed device comprises a pair of rollers positioned and adapted to engage opposite sides of the tape, and gear means interconnecting said rollers.

35 8. Apparatus according to claim 1, wherein there is provided tape deflecting means mounted on said frame on the opposite side of said nip from said tape feed device, and means for shifting said tape deflecting means between operative and inoperative positions depending on whether said machine is set for printing postage on tape or envelopes.

40 9. In a tape feeding mechanism for a postage printing machine capable of printing postage on envelopes or tape, the combination of, a frame, a platen rotatably mounted on said frame and adapted to rotate constantly while the machine is in operation, a printing head adapted to rotate cyclically, means forming a tape feed device mounted on said frame adjacent said printing head and platen and adapted when actuated to feed tape toward the nip between said printing head and platen, a driving member movably supported on said frame for movement into engagement with said platen so as to be driven thereby, means operable to move said driving member into

45 engagement with said platen, actuating means operatively associated with said printing head and with said driving member and actuated by said printing head during its cycle of operation to move said driving member into driving relation with said tape feed device, whereby said tape feed device is actuated to feed tape, a tape cutting device mounted on said frame between said tape feed device and said nip, means associated with said printing head, and means actuated by said last-mentioned means upon rotation of said printing head to actuate said tape cutting device whereby said tape cutting device is actuated once per revolution of said printing head.

50 10. Apparatus according to claim 1, wherein said tape feed device includes a driven roller, and said driving member comprises a roller.

55 11. Apparatus according to claim 9, wherein said next to last-mentioned means comprises a settable member mounted on said printing head and settable to be effective at one or the other

of two circumferentially spaced positions on said printing head, one of which effects cutting off of a relative short strip of tape and the other of which effects cutting off of a longer strip of tape.

12. In a tape feeding mechanism for a postage printing machine capable of printing postage on envelopes or tape, the combination of, a frame, a rotatable platen mounted on said frame, a cyclically rotatable printing head adjacent said platen, a tape feeding device mounted on said frame adjacent said printing head and platen and including a feed roller actuatable to effect tape feeding by said device toward the nip between said printing head and platen, a driving member movably mounted on said frame adapted to be driven by said platen and engageable with said feed roller to drive said roller, and actuatable means operatively associated with said printing head and with said driving member and actuated during the cycle of operation of said printing head to effect driving engagement between said driving member and said feed roller whereby said feed roller is driven through said driving member by said platen and tape is fed by said 25 tape feeding device.

13. In a tape feeding mechanism for a postage printing machine capable of printing postage on envelopes or tape, the combination of, a cyclically rotatable printing head having a driving element thereon, a driven system including a member engageable by said driving element whereby said driven system is periodically actuated by said printing head, a rotatable platen adjacent said printing head and engageable therewith during 30 the cyclic rotation thereof, a driven tape feed-

ing device adjacent the nip between said printing head and platen, a movable drive transfer mechanism operatively associated with said platen so as to be driven thereby and movable into and out of driving relation with said tape feed device, and means connecting said drive transfer mechanism to said driven system and responsive to actuation of said driven system by said printing head driving element to move said drive transfer mechanism into engagement with and accordingly drive said tape feeding device.

14. Apparatus according to claim 13 including means connected to a portion of said driven system and selectively manually operable to set 15 said system into operative or inoperative condition.

15. Apparatus in accordance with claim 13 wherein a spring-loaded tape cut-off device is provided, a trigger operatively associated with 20 said cut-off device to hold said device in its spring-loaded position, and means on said printing head for moving said trigger to trip said tape cutting device.
